UNITED STATES PATENT OFFICE.

LEON VANE KINGSBURY, OF SOUTH BEND, INDIANA, ASSIGNOR TO OLIVER CHILLED PLOW WORKS, OF SOUTH BEND, INDIANA.

LISTER-PLOW STRUCTURE.

Application filed March 30, 1923. Serial No. 622,857.

This invention relates to improvements in 5 lister plow structures and more particularly to the frame and draft construction,—one object of the invention being to provide a simple and efficient frame for a two-row 10 lister plow, which shall be capable of ready adjustment to space the plows different distances apart; which shall be adaptable for different types of listers, being capable of 15 use with various forms of draft means, and which shall be cheap to manufacture and yet substantial in construction.

With this object in view, the invention 20 consists in certain novel features of construction and combinations of parts as herein-after set forth and pointed out in the claim.

In the accompanying drawings—

Figure 1 is a plan view showing a lister 25 plow frame and draft means embodying my improvements.

Figure 2 is a side elevation, partly in section.

Figure 3 is a rear view, and

Figures 4 and 5 are views illustrating 30 modified draft means.

The plow frame comprises in its construction, parallel side members 1—2 which form 35 plow beams provided at their rear ends with integral plow standards 3, to which plow bases 4 are suitably secured. The respective side members or beams 1—2 are provided at their forward ends with inwardly 40 projecting beam or frame members 5—5 which are so disposed as to lie parallel with 45 each other throughout portions of their length. The members 5—5 are provided, each with a plurality of perforations 6 whereby the two sides of the frame may be 50 secured by means of bolts 7 in any desired 55 adjusted position relatively to each other. Flanged blocks 8 are disposed between the 60 overlapping portions of the frame members 5—5 and are perforated for the passage of the bolts 7,—said blocks serving to eliminate 65 any slack there may be between the bolts and the walls of the holes in the members 5—5 through which said bolts pass.

Two brace members 9—9 are disposed 70 between the rear portions of the side beams or members 1—2 and these brace members 75 overlap each other as clearly shown in Figure 1,—said brace members being adjustably connected together in the same manner as above described in connection with the forward members 5—5. Each brace member

is provided at one end with a rearwardly and downwardly extending portion 10 and these portions 10 lie against the respective side members 1—2 and against the standard portions at the rear ends of said members, 80 thus serving to reinforce and in effect constitute parts of the plow standards.

It will be readily seen that with my improvements the frame may be easily adjusted in width so as to space the plow 85 bases different distances apart and at the same time expand or contract the frame in width.

A bracket 11 embraces the overlapping members 9—9 centrally between the sides 70 of the frame and said bracket is provided with forwardly projecting ears 12. A similar bracket 13 embraces the forward overlapping frame members 5—5 centrally between the sides of the frame and this 75 bracket is provided with downwardly projecting arms or ears 14. A draft beam 15 is connected at its rear end to the bracket 11 by means of a bolt passing through the ears 12 of said bracket and through the rear portion of said beam. The draft beam also passes between the ears 14 of the bracket 13 and is secured thereto by means of a bolt 16. The draft beam extends forwardly 80 beyond the front end of the frame and the bracket 13 attached thereto and at its forward end, suitable coupling devices 17 are attached for connection of the lister with a tractor. Braces 18 are connected at their forward ends with the forward portion of 85 the draft beam and at their rear ends with the forward frame members 5—5 near the juncture of the latter with the side members or beams 1—2.

My improved frame is adaptable, not 90 only for use with a draft beam to be connected with a tractor but it is also adapted for connection therewith of draft means with which draft animals may be hitched. Such draft means are indicated in Figures 95 4 and 5. In this construction a draft beam 19 is connected at its rear end with the bracket 11 and intermediate of its ends with upwardly projecting arms 20 on a bracket 21 embracing the forward frame members 5—5. It will be observed that the draft beam 19 extends somewhat upwardly and 100 forwardly and its forward end is bent downwardly as shown at 22 and has secured thereto a sleeve bracket 23. This sleeve 105

bracket receives the spindle 24 of a forward carriage 25, said spindle being vertically adjustable relatively to said sleeve bracket. The carriage spindle is held in any desired adjustment by means of clamps 27 at the rear ends of the arms 28 of a clevis 29. The forward end of the frame and the draft beam are thus sustained by the said forward carriage and suitable hitch means for a team may be connected with the clevis 29.

The draft beam 19 will preferably be connected with the forward members 5—5 of the frame by means of brace rods 30.

While I have shown and described two forms of draft means for which my improved adjustable frame is adapted, it is to be understood that other forms of draft beam constructions may be connected with the frame in substantially the manner hereinbefore described in connection with the particular draft devices shown in the drawings.

Having fully described my invention what I claim as new and desire to secure by Letters Patent, is:

In a plow structure, the combination of side frame members having integral, overlapping front frame members, flanged blocks disposed between the overlapping members, said overlapping members each having a plurality of bolt holes, bolts to pass through the overlapping members and said flanged blocks, rear brace members between the side members and having overlapping perforated portions, flanged blocks disposed between said overlapping portions, bolts passing through said overlapping portions of said blocks, brackets embracing the forward and rear overlapping portions of the frame, and a draft beam connected with both of said brackets.

In testimony whereof, I have signed this specification.

LEON VANE KINGSBURY.
